UNITED STATES PATENT OFFICE

TADASHI D. GOMI, OF NEW YORK, N. Y.

DESIGN FOR A HAND BAG

Application filed June 10, 1930. Serial No. 36,013. Term of patent 3½ years.

To all whom it may concern:

Be it known that I, TADASHI D. GOMI, a subject of the Emperor of Japan, residing in the borough of Manhattan, in the city, county, and State of New York, have invented a new, original, and ornamental Design for a Hand Bag, of which the following is a specification, reference being had to the accompanying drawing, forming part thereof.

The drawing illustrates a perspective view of the hand bag showing my new design. The appearance of the opposite side is also ornamental in the same manner as the side shown.

I claim:

The ornamental design for a hand bag as shown and described.

TADASHI D. GOMI.
